(57) **CLAIM**

The ornamental design for a calendar and picture frame, as shown and described.

DESCRIPTION

FIG. 1 is a front, left side perspective view of a calendar and picture frame, showing my new design;

FIG. 2 is a left side perspective view thereof;

FIG. 3 is a rear view thereof; and,

FIG. 4 is a rear perspective view thereof.

The broken lines are for the illustrative purposes only and form no part of the claimed design.
